J. P. HENRY.
FLUID COUPLING.
FILED MAY 5, 1920.

Patented Jan. 30, 1923.

1,443,625

UNITED STATES PATENT OFFICE.

JOHN P. HENRY, OF COPPERHILL, TENNESSEE.

FLUID COUPLING.

Application filed May 5, 1920. Serial No. 379,023.

To all whom it may concern:

Be it known that I, JOHN P. HENRY, a citizen of the United States, residing at Copperhill, in the county of Polk and State 5 of Tennessee, have invented certain new and useful Improvements in Fluid Couplings, of which the following is a specification.

This invention relates to couplings for air or steam lines of railroad cars.

10 The object of the invention is to provide an automatic coupler of this character constructed and connected so that the draw heads of the cars to be coupled will be so adjusted by the coupling of the air or steam lines that said heads will couple simultaneously with or directly after the coupling of the air lines.

Another object is to so construct such a coupling that it will effectively connect the 20 air lines no matter how the car may be turned and when so coupled will insure the coupling of the draw heads.

With the foregoing and other objects in view, which will appear as the description 25 proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings a top plan view is shown having parts broken out and 35 in section, the coupling being shown in operative position and the draw heads used in connection therewith represented in dotted lines.

In the embodiment illustrated, the couplers 40 constituting this invention are shown in the position assumed when two cars are equipped therewith and coupled thereby, the two main air pipe lines to be connected being shown at A and A', respectively.

45 The coupler constituting the invention comprises four cylinders, 1, 2, 3 and 4, arranged in pairs, parallel with each other, the two cylinders 1 and 2 being carried by one car and those 3 and 4 by the opposed car to be connected. All of these cylinders are exactly alike, except that one of each pair carries guide means for the connecting pipe of the co-operating cylinder of the other pair as will be presently more fully described.

55 Each cylinder is closed at its front end by an integral head 5 having a central opening

and a laterally extending annular flange 6, and at its rear end has a similar flanged head 7 to which is bolted an auxiliary head 8.

Auxiliary heads 9 are mounted on the 60 front ends of the cylinders and bolted to the flanges 6 of the heads 5 thereof. Outside the heads 9 are mounted solid rubber gaskets or packings 10 which have inwardly projecting tubular extensions 11 positioned within 65 the cylinders and on the outer faces of these packings are arranged packing glands 12 bolted to the cylinder heads. The extensions 11 will provide the resiliency necessary to permit relative movement of the cylinders 70 when the train is in motion. Inner packing glands 13 are arranged in each cylinder and are made cup-shaped to fit the inner ends of the tubular extensions of the packings with lateral flanges carrying hooks 14 with 75 which are engaged eye bolts 15 which extend through the outer packing glands 12, the packing 10 and the cylinder heads. This connection of the hooks 14 with the eye bolts 15 securely hold the glands 13 in position 80 and assist in retaining the outer glands and the packings in operative position.

Connectors in the form of pipes 16 are permanently attached to and carried by the cylinders 1 and 4 and are designed to be detachably engaged with the co-operating cylinders 2 and 3, the cylinder 3 being arranged opposite cylinder 1 and cylinder 4 opposite cylinder 2 when the parts are in coupling position as is shown clearly in the 90 drawings. These pipes 16 extend through the extensions of the packings in cylinders 1 and 4 and are threaded at their inner ends to receive nuts 17 which hold them in connected relation relative to their respective cylinders, the washer 18 being loosely mounted on each pipe between nuts 17 and the inner packing gland 13.

95 Stops 19 are carried by the pipes 16 outside the cylinders 1 and 4 and are designed 100 to prevent the pipes from slipping rearwardly into the cylinders, said stops being positioned on the pipes so as to permit a certain longitudinal play of the pipes 16 in the heads of the cylinders which carry them. 105

Carried by the packing glands 12 of cylinders 2 and 3, and preferably made integral therewith are cone-shaped guides 20, their smaller ends being arranged inwardly with their flared mouths extended outwardly and 110 which are designed to receive the free ends of the pipes 16 and to direct them into cou-

pling position. By so constructing these guides 20, it will be obvious that the pipes 16 may enter when the cars to be coupled are out of alignment and being tapered toward their inner ends will direct said pipes into operative position and force the couplers to move so that the cylinders 2 and 4 and 1 and 3 will aline longitudinally as shown in the drawings.

- 10 Short hose connections 21 are connected at one end with nipples 22 which extend through the rear heads of all the cylinders and the other ends of these hose are connected with short pipes 23 united by couplings 24 which also connect with the main air lines A and A'. Cut-off valves 25 are located in the pipes 23 and a similar valve in the air pipes A and A' adjacent the T-couplings 25. These valves 25 and 26 have 15 actuating arms 27 here shown L-shaped to properly position them for connection with actuating rods 28 which extend in planes at right angles to the axes of the cylinders with their free ends positioned beyond the sides 20 of the car for convenient operation by the brakeman without necessitating his going between the cars. It is of course to be understood that when these rods 28 are moved in one direction they will open the valves 25 which they control and admit air to the cylinders which on entering the cylinders from the nipples 22 will pass out through the pipes 16 into the cylinders of the other car and back to the air line of said car thereby bringing the two air lines A and A' into communication. The actuation of the rods in the other direction will close said valves and cut off air from the cylinders when the cars are to be uncoupled.
- 10 Carried by the inner side wall of each cylinder is a bracket 29, here shown T-shaped and bolted to the cylinder with the shank portion thereof extended laterally. Each bracket shank has an upstanding lug 30 which is secured to the draw head 31 of the car on which the coupler is mounted, the two cylinders 1 and 2 being fixed to the draw head of the car on which they are mounted while the cylinders 3 and 4 are fixed to the

draw head of the car to be coupled. These 50 draw heads 31 are equipped with the usual couplers 32 which may be of any desired construction and are shown in the drawings arranged in juxtaposition ready for engagement when the cars are moved toward each other, the pipes 16 being in partially coupled position, so that when the cars move toward each other they will move into cylinders 2 and 3 until the stops 19 abut the glands 12 of the opposed cylinders, and 55 when in this position the draw head couplers 32 will have become engaged and the cars coupled together.

From the foregoing description, taken in connection with the accompanying drawings, the advantages of the construction and of the method of operation will be readily apparent to those skilled in the art to which the invention appertains and while I have described the principle of operation of the 60 invention together with the device which I now consider to be the best embodiment thereof, I desire to have it understood that the device shown is merely illustrative and that such changes may be made as are within the scope of the claimed invention.

Having thus fully described my invention, what I claim as new and desire to secure by Letters Patent, is:—

A fluid coupling including a pair of aligned 80 coaxing fluid pressure containing cylinders, a gasket detachably carried by each cylinder and equipped with a tubular resilient extension projecting into the cylinder, a guide member supported on one of the gaskets and 85 extending toward the other, and a tube arranged through the gasket and tubular extension of one of the cylinders and projecting appreciably beyond the latter for slideable engagement through the guide member, 90 gasket and tubular extension of the second of said cylinders, substantially as described.

In testimony whereof I affix my signature in presence of two witnesses.

JOHN P. HENRY.
